APPARATUS FOR THE MANUFACTURE OF
RUBBER TUBES

Alfred A. Glidden and Thomas M. Knowland,
Watertown, Mass., assignors to Hood Rubber
Company, Inc., Watertown, Mass., a corpora-
tion of Delaware

Application October 10, 1929, Serial No. 398,620

9 Claims. (Cl. 18—24)

This invention relates to the manufacture of vulcanized rubber tubes, particularly of inner tubes for pneumatic tyres, and has for its object the construction of tubes of this character directly from latex, or its concentrated modification, revertex, by agglomeration of the individual solid particles suspended in the water emulsion by progressive and regulated evaporation of the said water which conserves the association of the component of said unit particles, as distinguished from coagulation, as by means of acid agents, which is characterized by extrusion from the rubber coagulum with the water of emulsion, of the proteids, sugars, etc., normally associated with the rubber particles.

The invention presents three aspects, namely: process, product, and apparatus, and is herein described in all three. The respective performances of the elements or factors of apparatus, in their necessary functional order and succession, are steps of the process. The process or series of steps requires the essential elements of the apparatus, as described herein, for its performance. The performance of the essential elements of apparatus, and the process therein involved, inevitably results in the product herein described.

In its process-aspect, the invention is characterized by application of a foundation film of rubber-emulsion (with usual composition-ingredients distributed through it, such as zinc oxid, sulfur, an accelerator) to a mandrel, the material of which is preferably a metal inert to latex, and the surface non-porous and impenetrable, partially drying the said film, under conditions which maintain uniform thickness of the film, applying a second film coating on the foundation film before the exposed surface of the latter has, by loss of water, reached irreversibility, partially drying the second or outer film under conditions similar to those imposed on the foundation film, applying a third film to the still reversible material of the second, and so on, until the desired body or thickness of tube has accumulated, when the tube, supported by the mandrel, may be thoroughly dried, then stripped from the mandrel, and vulcanized; or vulcanized on the mandrel and afterward stripped.

In its apparatus aspect, the invention is characterized by means for applying, in succession and superposition, upon a mandrel, coatings of a latex composition, means for immersing and emerging, in alternation, the lower segment or limb of the mandrel in a pool of the emulsion, and means for changing the rate of rotation of

the mandrel on its axis to suit the conditions, respectively, for applying and setting each coating of emulsion.

In its product aspect, the invention is exemplified by a tube of latex rubber (or rubber composition) which, though built to desired thickness by accumulation of successive latex emulsion coatings, is free from lamination, an integer in structure, homogeneous, and free from any "grain" effect; a tube which, when completed, conserves in its constitution the whole of the ingredients in suspension in the original emulsion, and the characters of the original rubber unit particles, altered only by aggregation and coalescence, consequent on elimination of the water of suspension, and by vulcanization.

Herein, the word "latex" is employed as meaning either normal latex, or its reversible concentrate, revertex.

The essentials of the process and characteristics of the product may be explained and understood in connection with the drawings hereto annexed, in which Figures 1 to 4 inclusive are diagrammatic.

Fig. 1 illustrates the mode in which successive film coatings of prepared revertex composition are applied in building a tube;

Fig. 2 the tube mandrel removed from contact with the composition-supply;

Fig. 3 a segment in section of mandrel and first film coating;

Fig. 4 a similar segment-section of mandrel, first coating and second coating;

Fig. 5 is an end-elevational view of apparatus comprising the elements illustrated in Figs. 1 and 2;

Fig. 6 is a view, partly in front elevation, partly in section, of the same;

Fig. 7 is a section on line 7—7 of Fig. 5; and

Fig. 8 is a wiring diagram.

First referring to the elementary Figs. 1 to 4, inclusive:—liquid latex composition R, (of whatever concentration may be desired, preferably more concentrated than normal latex) containing, for instance, zinc oxid, finely divided sulfur, and an accelerator, is placed in a trough T. A tube mandrel, M, of aluminum or other metal which does not affect latex, with a smoothly polished surface, is mounted on centers above the trough, substantially parallel with the level surface of the composition R. Mechanical adjuncts (not shown in Figs. 1 and 2) are provided whereby the mandrel M and trough T may be made to approach or recede from each other while main-

taining the said parallel relation. Preferably this will be accomplished by raising and lowering the trough T.

The first film coating of latex composition is applied by raising the trough T until a narrow segment of the mandrel is immersed in the composition. Before making this contact the surface of the composition R should be cleared of any skin that may have formed upon it. At or 10 just before the contact is made, the mandrel M is started to rotate on its axis, but rather slowly, say at a surface velocity about seventy-five inches per minute. When the mandrel has made one full rotation, the contact between 15 mandrel and composition is quickly broken as by lowering the trough T, and immediately after emersion the mandrel is caused to rotate on its axis (which is kept horizontal) at a much higher speed than before; the number of rotations per 20 minute may vary within quite wide limits, provided the alternation of any given point on the mandrel surface, between ascent and descent, be sufficiently frequent to prevent the film or envelope of latex from running circumferentially of 25 the mandrel to produce irregularities in thickness of the film. For this purpose a surface velocity of about one hundred and eighty inches per minute has been found suitable. The coated mandrel is kept rotating at the relatively high 30 rate until the evaporation of the water from the coating of composition has so far reduced the water-percentage as to produce an increase of viscosity and plasticity therein which practically fixes the coating in uniform thickness, 35 but not so far as to produce irreversibility in the composition at and near its exposed surface, if, as will be almost invariably the case, the composition-layer on the mandrel is to be built up by successive applications of composition from 40 the supply R.

The rate of rotation of the mandrel will be governed by the temperature, humidity, and rate of circulation of the air which effects the evaporation of water from the film coating, and these 45 factors should be kept constant in value by suitable controls. A smooth and impervious mandrel surface is preferable to one which is porous, not only because of the facility with which a completed tube is stripped from the smooth 50 mandrel, but also because the time of exposure to drying air can be more accurately determined when the extraction of water from the composition film is effected in one radial direction only.

The foundation coating having been set, as 55 above described, the application of the next coating follows. The mandrel M, now carrying a layer of composition set to a practically firm consistency, which, however, retains enough of the emulsion liquid to preserve the reversible 60 character at the exposed surface, is again brought into segment-immersion relation with the composition supply R in trough T, its rate of rotation being slowed down to give a surface velocity of about seventy-five inches per minute, so that the second film coating shall be evenly taken up. Just prior to the application 65 of the second coating the condition of the first is as illustrated in Fig. 3 (the coating-thickness in this figure and in Fig. 4 being exaggerated). 70 The water of the supply-emulsion is migrating in the direction of the arrow through the coating L¹, and the intimacy of agglomeration of the suspended solids in the film increases in the same direction. The application of the next 75 coating L² over L¹ (Fig. 4) stops evaporation

from the surface of coating L¹, in which the remaining water proceeds toward uniform redistribution. At the same time water from L² migrates into L¹, reversing the progress of agglomeration of the revertex solids. The mandrel M, being as before immersed from the composition supply R, and given its higher rate of 80 rotation, water-evaporation from the outer surface of coating L² begins, and presently the migration of water in both L¹ and L² proceeds centripetally; the momentary reversion of migration from L² to L¹ will have integrated the two 85 coatings, so that no distinction of lamination will thereafter develop between them.

The foregoing alternations of envelope-application and evaporation having been continued until the desired thickness of tube is acquired the agglomerated material on the mandrel will be dried thoroughly, or until it is in condition for vulcanization; the mandrel with the uncured tube on it may then be placed in a suitable vulcanizing apparatus, and cured; or the tube may be stripped first and vulcanized later. 90

If the tube is to be used as an inner tube of a pneumatic tyre, the preferred mode of manufacture will comprise attachment of a valve base to the unvulcanized tube while on the mandrel, removal of the tube from the mandrel by the aid of compressed air, attachment of the valve, splicing the ends of the tube, inflation and vulcanization in any usual manner. 100

Observed advantages of the process above described are: That each layer of the supply-emulsion, attached to the form represented by the mandrel (with or without previously set 110 layers) being quite thin, is by the air-drying to which it is subjected reduced to a very nearly homogeneous condition of agglomeration of the latex-solids (as distinguished from the other 115 solids which enter into the vulcanizable composition, and which are included in the agglomerating colloidal net of latex-solids) so that in a tube of considerable wall-thickness, produced by the accumulation of thin layers, the structure is homogeneous and the residual water 120 small in percentage and uniformly distributed. A relatively short period of air drying of the completed tube, at temperatures below boiling point suffices to eliminate this residual water; thus the tube is soon in condition for vulcanization 125 and can be cured without danger of any cellular sponge formation in its wall. Tubes formed in the manner above described are free 130 from any "grain", are exceptionally strong and resistant to penetration, tearing, or checking.

The distinction between agglomeration and coagulation of latex particles is well recognized, though the two changes in physical state may be sequent in the relatively abrupt transformation to coagulation. Transformation of a latex 135 emulsion into a virtually solid consistency by agglomeration by the above described agency of spontaneous evaporation is a relatively slow and gentle process; its progressive stages are difficult to detect directly but may with confidence be inferred by observing the subsidence 140 of Brownian movement in test samples taken at successive intervals. It is believed, and the qualities of agglomerated latex confirm the belief, that this mode of transformation of latex 145 to a virtual solid conserves in the constituent particles their originally associated constituents, and does not break the unit-aggregates of latex particles. The strength and toughness of the resultant product, as in a tube made as above 150

described, as well as other valuable properties, demonstrate a radical difference from like articles of manufacture made from coagulated and milled rubber. Moreover, forced extraction 5 of the water from a latex, as by filtration under pressure-differential, breaks a considerable portion, if not all, of the original rubber-particle units, and carries off valuable ingredients associated with rubber in latex.

10 There are still other methods than simple spontaneous evaporation of its liquid by which a latex may be agglomerated, as by gradually acidifying an alkaline latex with an acid coagulant; the formation of a tube by agglomeration 15 by such a method would require a technique more delicate and difficult than the evaporation method, which is therefore regarded as preferable.

Referring now to Figs. 5 to 8 inclusive, of the 20 drawings: In these figures there is illustrated an apparatus which in its essential members and their related operations is the same as the apparatus illustrated in Figs. 1 to 4, inclusive, but shows adjunctive mechanical environment there- 25 of adapted to actuate the principal apparatus elements in the same manner as that described in connection with the explanation of the process. In the apparatus as more fully equipped, the mandrels are multiplied, but each 30 in turn performs its function in relation to the latex trough or reservoir exactly as in the elementary arrangement and manipulation of the single-mandrel. In the intervals also between successive immersions in the latex pool, each 35 mandrel is rotated with relative rapidity and given time adequate to set the last applied latex coating to the stated condition which is short of that of reversibility of the surface. This apparatus is particularly designed to permit the 40 concomitant manufacture of a plurality of tubes, thus comprising supporting and conveying means which is arranged to carry a plurality of rotary mandrels about a circuit, one part of which is in juxtaposition to a dipping vat that 45 contains the liquid which is to be applied to the mandrels in successive films or layers. To this end the supporting means is preferably ar- 50 ranged to be locked in a plurality of positions, each one of which corresponds to the location 55 of one of the mandrels in juxtaposition to the dipping vat, whereby the supporting means may have an intermittent movement and be effective in bringing successive mandrels into a position where the rotary surface thereof may contact the liquid contained in the vat.

60 Preferably, means are provided to cause the vat to be lifted to bring the surface of the contained liquid into contact with a narrow seg- 65 mental portion of a juxtaposed mandrel. In order to permit the effective, even and uniform application of the latex layer or film to the mandrel, the speed of the latter is preferably comparatively low when its surface is in contact with the liquid; while in order to permit the 70 satisfactory drying of the latex or revertex and to permit the applied layer of the same to main- 75 tain a uniform thickness without the occurrence of bubbles or wrinkles, the speed of rotation of the mandrel is increased, i. e., preferably more than doubled substantially as soon as it leaves the surface of the liquid. To this end, the present machine affords means automatically controlling the speed of the rotary mandrels. Thus, we prefer to provide individual driving 75 factors such as electric motors for the mandrels,

these motors receiving their current from a common source of supply by means of contacts engaging circular or segmental conductors which are arranged so that the motor that drives the mandrel in juxtaposition to the vat may rotate 80 at a lower speed than the other motors.

As shown in Figs. 5 and 6, the supporting and conveying means for the mandrels may comprise a rotary frame or support 1 which is provided with an axle 2 having its ends mounted upon supporting frames or standards 3; the support 1 preferably comprises parallel circular plates 85 7 and 7^a, which are spaced from each other at a suitable distance to permit the location of substantially horizontal cylinder mandrels M 90 of suitable length therebetween.

95 Preferably each mandrel M comprises a hollow metal cylinder of suitable metal, such as aluminum, and has a comparatively smooth exterior surface. Plugs 12, provided with shoulders 9, are arranged to interfit with the ends of the cylindrical mandrels, having central openings 8 for interfitting engagement with axial supports that are carried by the parallel plates 7 and 7^a of rotary support 1. Thus, as shown in 100 Fig. 6, supporting plate 7 may carry a plurality of rotatable elements 18 mounted in and slidable through openings 17; these elements have heads 19 engaging sleeve-like stops 20 that are secured to the plate 1. The opposite end of each rotatable element preferably has a frusto-conical head 21 that is urged by a spring 22 into interfitting engagement with an opening 8 in a plug 12. Each member 20 and opening 17 in plate 1 105 cooperate in providing a bearing in which an 110 axial support 18 may rotate.

At the opposite end of each mandrel, we preferably provide a rotatable stub shaft 25 extending through the plate 7^a and carrying a frusto-conical member 21^a which engages the 115 opening in the corresponding plug. The outer end of each stub shaft preferably is provided with a worm gear 26 which engages a worm 27 upon the end of the main shaft of an electric motor 29. Thus each motor 29 is effective 120 through gearing 26-27 in rotating the corresponding stub shaft 25 and the adjoining mandrel. Obviously a mandrel M may be removed by compression of the corresponding spring 22 and consequent movement of the corresponding 125 part 21 out of engagement with the plug 12, whereupon the opposite plug may be removed from engagement with the member 21^a.

130 A vat or trough T is disposed below axle 2 of the rotary support, being mounted upon a suitable frame 31, the ends of which are secured to non-rotatable nuts 33 that engage jack screws 34 at either end of the machine. These jack screws preferably are vertically disposed and rotate in bearing brackets 36 and 37 that are 135 mounted on the standards 3. The lower end of each jack screw carries a beveled gear 39 which meshes with a corresponding gear 40 upon a horizontal shaft 41. A hand crank 44 is ar- 140 ranged to rotate shaft 41 by means of sprockets 45 and 46 and a chain 47. It is thus evident that rotation of crank 44 is effective in rotat- 145 ing shaft 41 and the beveled gears 39 and 40 to cause the jack screws 34 to turn in unison, thus lifting or lowering frame 31 and trough T.

150 Means are preferably provided to facilitate the stopping of the conveyor member or rotary frame in any one of a plurality of positions corresponding to the preferred operative juxtaposition of any one of the rotary mandrels M

to the trough T. For this purpose, lugs 45 corresponding in number to the mandrels, may be provided upon the outer face of plate 7, these lugs being shaped to engage a suitable locking block 52 carried by a plunger 53 that is normally pressed into engagement with a lug 45 by a compression spring 54 (Fig. 7). A bracket 55 upon the frame member 3 supports the spring and plunger, while a handle 56 permits its movement out of engagement with the lug. Preferably the member 52 has a curved edge portion 52^a which permits the ready engagement of the side of the lug with the locking block as the frame is rotated, the lug snapping into engagement with the corresponding intermediate recess upon the face of the block to lock the frame in position; unless the plunger is moved or held out of its normal position.

Preferably each of the electric motors 29 receives its current from a common source, being connected to brushes which are mounted on the rotatable plate 64 and are resiliently urged into engagement with segmental conductors 60 and 60^a or 60^b within a fixed contact box 61. Preferably the inner conductor 60 is circular and may continually engage a brush 62 that is connected with each motor, the segmental conductor 60^b forms the major portion of a circle, the short segmental conductor 60^a being located between its ends. An individual contact 63 for each motor thus is normally in engagement with either the outer segmental conductor 60^b or the segmental portion 60^a, there being a short gap of non-conducting material between these conductors. Suitable variable resistances R¹ and R² may be arranged in series with the conductors 60^a and 60^b, the resistance R² in series with the conductor 60^a being arranged normally to provide a fairly high resistance so that the voltage of the current flowing through the motor 29 which has its brush 63 in contact with the conductor 60^a will be materially less than that passing to the remaining motors. Preferably the connections are so arranged that less energy will thus be imparted to the motor which is driving the mandrel that has been stopped in juxtaposition to vat T. Under normal operating conditions the speed of each mandrel will therefore be materially reduced as it arrives at a position at the lowest point in its path, i.e., at a point adjoining the vat.

Preferably the axis 2 of the frame 7 and the axes of the individual rollers or mandrels M are so disposed that the latter have a slight inclination to the surface of the liquid contained within vat T, i.e., a slight inclination to the horizontal. Thus, the lowermost limit, or longitudinal profile, of the mandrel is slightly displaced from parallelism with the surface of liquid composition in the trough or vat; and, when the latter is raised to effect immersion of the lower sector of mandrel surface, the contact between the lower limb of the mandrel and the surface of the liquid begins at one end of the mandrel and progresses rapidly to the other end.

This mode of making immersion is less likely to allow inclusion of bubbles in the coating than immersion of the entire lower limb of the mandrel at the same instant.

70 The revertex composition which may contain, for example, zinc oxid, finely divided sulfur and an accelerator is placed in the vat T, and the frame 1, as shown, may be rotated by hand or any suitable intermittently operable driving means, may be employed for this purpose, the

support 1 being automatically locked by the block 52 when one of the mandrels M is brought into juxtaposition with the vat T. Normally, the latter is disposed at a level which prevents the contact of such a mandrel with the surface 80 of the contained liquid. The crank 44 may then be operated to lift the frame 31 and vat T so that a narrow segmental portion of the mandrel is in contact with the liquid in the vat. Due to the slight inclination of the axis of the mandrel 85 in relation to the liquid surface, there is a progressive contacting of the liquid surface with the surface of the mandrel which is effective in forcing out air from between these surfaces and which avoids the tendency of air clinging to the 90 mandrel to form bubbles or blisters in the deposited film. The mandrel preferably is permitted to rotate for one revolution, thereby picking up a thin film or a coating of the latex or revertex. The handle 44 is then operated to 95 lower the vat from its position where the mandrel engages the liquid surface and the frame 1 is rotated so that the succeeding mandrel is disposed above the vat and so that the coated mandrel is moved out of juxtaposition to the vat. 100 This automatically results, due to the arrangement of the segmental conductors, in the rotary acceleration of the last coated mandrel. Thus the mandrel, while being coated, may have a comparatively low speed to permit the depositing 105 of a thin layer of liquid upon its surface; practically as soon as it leaves the liquid surface, the rotary speed of the mandrel is increased, thus preventing the formation of wrinkles or irregular ridges upon the mandrel, in other words insuring the retention of a thin uniform film. The higher speed at which the mandrels rotate after leaving the vat also aids in the drying of the latex or the removal of the excess moisture. Obviously the operation of coating the mandrel 110 may be repeated until each of the mandrels upon the support has received a thin film of latex.

Preferably the support is not rotated at such a rate as to bring the first coated mandrel into 120 contact with the liquid until sufficient time has elapsed to permit the partial drying of the first film to a point approaching irreversibility. Thus, as the succeeding coating operations are performed, there will ordinarily be a period of 125 delay between the successive mandrel coatings. While, as shown, the rotary support 1 and the vat 30 may both be manually moved or operated, it is evident that automatic means may be provided for either or both of these purposes. 130

We claim:

1. In apparatus of the character described, a horizontal cylindrical mandrel rotatably mounted with its lowermost limit slightly inclined to the horizontal, means to rotate the same, a trough adapted to contain latex emulsion, said trough located below the said mandrel, and means for relatively moving the mandrel and trough to immerse the lower limb of the mandrel in, and remove it from, the latex emulsion in the trough. 140

2. In apparatus of the character described, a horizontal cylindrical mandrel rotatably mounted with its lowermost limit slightly inclined to the horizontal, means to rotate the same, a trough 145 adapted to contain latex emulsion, said trough located below the said mandrel, and means for relatively moving the mandrel and trough to immerse the lower limb of the mandrel in, and remove it from, the latex emulsion in the trough. 150

- the means for rotating the mandrel adapted to impart different rates of rotation thereto.
3. Apparatus of the class described comprising a plurality of horizontal cylindrical mandrels, a common supporting and conveying means, said means being arranged to move the mandrels about a circuit while permitting their rotation about their individual axes, means for rotating the mandrels, a vat arranged to contain liquid to be contacted by the surface of each mandrel in one portion of its circuitous path, each mandrel having its axis slightly inclined to the horizontal as it is brought into juxtaposition to the vat, whereby its surface is progressively brought into contact with the liquid surface.
4. Apparatus of the class described comprising a plurality of mandrels, a common supporting and conveying means, said means being arranged to move the mandrels about a circuit while permitting their rotation about individual axes, a vat arranged to contain liquid to be contacted by the surface of each mandrel in one portion of its circuitous path, driving means to cause the rotation of the mandrels and control means associated with the driving means, said control means automatically causing the more rapid rotation of a mandrel as it moves out of juxtaposition to the vat.
5. Apparatus of the class described comprising a plurality of mandrels, a common supporting and conveying means, said means being arranged to move the mandrels about a circuit while permitting their rotation about their individual axes, a vat arranged to contain liquid to be contacted by the surface of each mandrel in one position of its circuitous path, locking means automatically operable to stop the supporting and conveying means in a plurality of positions corresponding to the location of the respective mandrels in juxtaposition to the dipping vat, driving means to cause the rotation of the mandrels and control means associated with the driving means, said control means automatically causing the more rapid rotation of a mandrel as it moves out of juxtaposition to the vat.
6. Apparatus of the class described comprising a plurality of mandrels, a common supporting and conveying means, said means being arranged to move the mandrels about a circuit while permitting their rotation about their individual axes, a vat arranged to contain liquid to be contacted by the surface of each mandrel in one portion of its circuitous path, locking means to stop the supporting and conveying means in a plurality of positions corresponding to the location of the respective mandrels in juxtaposition to the dipping vat, individual driving means for each of said mandrels, and control means associated with said driving means and arranged to cause the more rapid rotation of each mandrel as it leaves the vat and a decrease in its speed before being brought into juxtaposition to the vat.
7. Apparatus of the class described comprising a plurality of mandrels, a common supporting and conveying means, said means being arranged to move the mandrels about a circuit while permitting their rotation about individual axes, a vat arranged to contain liquid to be contacted by the surface of each mandrel in one portion of its circuitous path, individual driving motors for each of said mandrels, a common source of current for said motors, and conductors to transmit current from said source to the motors, a resistance in series with one of said conductors arranged to cause the supply of a smaller amount of current to the motor that is driving the mandrel in juxtaposition to the vat than to the other motors.
8. Apparatus of the class described, comprising supporting and conveying means, a plurality of rotatable mandrels carried by said means, a dipping vat arranged to contain liquid to be contacted by in turn the respective mandrels, means for rotating the mandrels, said means being arranged automatically to effect the rotation of each mandrel at a relatively low speed when in juxtaposition to the tank, and at a relatively high speed thereafter.
9. Apparatus of the class described, comprising supporting and conveying means, said means comprising spaced parallelly disposed portions, a plurality of rotatable cylindrical mandrels spanning the space between said support portions, driving means associated with one of said support portions and comprising elements adapted to interfit with one end of each of the cylindrical mandrels and, axial elements carried by the other supporting portion and arranged to interfit with the other end of each of the cylindrical mandrels, said axial elements each having a compressible portion, whereby the opposite end of the mandrel may be moved out of interfitting engagement with the corresponding driving member by the compression of the said portion of its axial element.
